UNITED STATES PATENT OFFICE

HENRY E. PETERSON, OF DES MOINES, IOWA

DESIGN FOR A COMBINATION CIGARETTE HOLDER, DISPENSER, AND ASH TRAY

Application filed February 18, 1931. Serial No. 38,712. Term of patent 3½ years.

To all whom it may concern:

Be it known that I, HENRY E. PETERSON, a citizen of the United States, residing in Des Moines, in the county of Polk and State of Iowa, have invented a new, original, and ornamental Design in a Combination Cigarette Holder, Dispenser, and Ash Tray, of which the following is a specification, reference being had to the accompanying drawings, forming a part thereof.

Fig. 1 is a front side view, and Fig. 2 is a top plan view of my combination cigarette holder, dispenser, and ash tray, showing my new design.

I claim:

The ornamental design for a combination cigarette holder, dispenser, and ash tray, as shown.

HENRY E. PETERSON.
